(57) **CLAIM**

The ornamental design for a display screen with graphical user interface displaying a bottom of screen scroller for scores for a fantasy sports application as shown and described.

DESCRIPTION

FIG. 1 is a first image of a display screen with graphical user interface displaying a bottom of screen scroller for scores for a fantasy sports application showing the claimed design; FIG. 2 is a second image thereof; FIG. 3 is a third image thereof; and, FIG. 4 is a fourth image thereof.

The appearance of the animated graphical user interface sequentially transitions between the images shown in FIG. 1 through FIG. 4 including the reverse order. The process or period in which one image transitions to another forms no part of the claimed design.

The outermost broken lines depict a mobile device, which is the environment of the design, and form no part of the claimed design. The remaining broken lines illustrate the display screen and portions of the graphical user interface that form no part of the claimed design.
